UNITED STATES PATENT OFFICE.

DOUGLAS WHITAKER, OF LEICESTER, ENGLAND.

SHIELD TUNNELING-MACHINE.

1,311,143.

Specification of Letters Patent. Patented July 22, 1919.

Application filed May 13, 1919. Serial No. 296,951.

To all whom it may concern:

Be it known that I, DOUGLAS WHITAKER, subject of the King of Great Britain, residing at Leicester, in the county of Leicester, 5 England, have invented certain new and useful Improvements in or Relating to Shield Tunneling-Machines, of which the following is a specification, reference being had therein to the accompanying drawing.

10 This invention relates to shield tunneling machines and concerns those of the self contained type *i. e.* wherein the driving means such as motor, gearing and other parts and the advancing means such as jacks, are arranged inside the shield or outer cylindrical case.

With machines of this class there is a tendency in use, owing to the torque, for the outer case or body to creep circumferentially 20 in the bore or tunnel, and when this occurs the driving means and other parts contained and fixed within the case are brought to a more or less canted position.

The creeping or turning of the case or body within the bore or tunnel is more marked with some kinds of earth or material than it is with others, but it is found that generally there is a creeping rotation of the outer body as the machine is advanced 30 with the aforesaid result that the internal driving and other parts become moved from the upright position.

It is necessary, or at any rate very desirable, that the internal parts of machines of 35 this type should be maintained in an upright position or substantially so, and this is particularly important when the machine is equipped with water tanks and pumps for the hydraulic actuation of the jack or rams.

40 With a view to counteracting the circumferential creeping tendency, the cylindrical case or body has in some instances been furnished with exterior devices such as wings or ribs; these however, are liable to be 45 broken off or bent or distorted by contact with stones or hard resisting material as the machine is advanced.

The present invention has for its object to improve the construction of tunneling 50 machines of the class referred to whereby in spite of any turning or circumferential creeping of the outer case or body which may occur the internal parts of the machine

may be maintained in an upright or other desired position.

To this end those internal parts of the machine which are to be maintained upright or in definite positions relatively to the horizontal or vertical plane, are arranged in such a manner as to be capable of adjustment 55 within the outer cylindrical body so that in the event of the latter turning within the bore or tunnel, the said parts can, by the aforesaid adjustment, be restored to their correct position.

The invention therefore, comprises a shield tunneling machine of the type herein referred to characterized by the feature that the internal structure or one or more parts of same is or are capable of movement relatively to the outer case or body, for the 60 purpose hereinbefore mentioned.

Means are combined with the internal movable part or parts and the outer case or body to fasten said movable part or parts in 65 position after adjustment.

According to one manner of carrying out the invention the whole of the internal parts of the machine are arranged to be capable of rotative adjustment within the outer case 70 for which purpose said parts are attached to a suitable frame or structure suitably mounted in the cylindrical case so as to be rotatable therein.

In further describing the invention reference will be made to the accompanying drawing wherein a concrete example of the invention is illustrated.

In the drawing referred to:

Figure 1 is a sectional side view of a 75 shield tunneling machine having the internal structure arranged in such a manner as to be rotatably adjustable within the cylindrical outer case.

Fig. 2 is a cross section of the same taken 80 on the line *a—a* of the Fig. 1 viewed from the right.

In both figures of the drawing, like parts are designated by the same reference characters.

In the tunneling machine shown in the drawing, 1 is the cutter head, 2 is the cutter shaft, 3 the driving gear and other associated parts, 4 the motor, 5 the jacks or rams and 6 the cylindrical case or body which 85 forms the shield. The machine is moved

forward in the usual manner by the action of the jacks or rams 5 which take a bearing against the end of the lining 7 the latter being placed in position in sections as the 5 machine is advanced.

According to the present improvement, the whole of the internal parts are supported by a frame or structure shown generally at 8 and this frame is mounted by 10 means of rollers or wheels 9 upon internal circumferential rails or tracks 10 in the cylindrical case 6 and is thereby able to turn in the latter.

The turning of the frame or structure 8 15 may be effected by any convenient means. For example, one or more screw jacks or equivalent devices may be employed such device or devices operating between suitable parts fixed to the frame and outer case re- 20 spectively.

A convenient construction and arrangement of the aforesaid screw jacks for moving the frame 8 around inside the cylindrical case 6 is shown in Fig. 2. Each jack consists of a screwed rod 11 furnished with a handwheel 12 said rod engaging with a nut 13 pivotally mounted in a bracket 14 attached to the frame 8. The opposite end of the rod 11 engages another nut 15 which is 25 connected by links 16 (Figs. 1 and 2) with an annular flange 17 on the inside of the cylindrical case 6 said flange as shown in Fig. 2 having a series of holes 18 so that the links 16 may be connected thereto at any 30 suitable point, and the point of connection may be altered as necessary when the frame 35 is turned in the case 6.

The opposite ends of the rod 11 engaging with the nuts 13 and 15 are oppositely screw threaded so that by turning the hand wheel 12, the distance between the bracket 14 and the point of connection 19 on the annular flange 17 is varied to turn the frame 8 one 40 way or the other.

45 In the arrangement shown two screw jacks such as just described are provided on each side of the frame 8 and it will be obvious that to change the position of the frame within the case 6 the jacks on one side must 50 be slackened while those on the opposite side are tightened. The tightening of the jacks

on the opposite sides of the frame 8 after adjustment of the latter firmly fastens the frame in position in the case 6 by pulling the rollers or wheels 9 down upon the rails 10. 55

From the foregoing description it will be readily understood that if during the advance of the machine the shield or outer case 6 turns within the bore 20, the internal parts may be restored to proper position by adjustment of the jacks the anchorage points 19 of which may be changed around the flange 17 to suit requirements.

By mounting the jacks or rams 5 or equivalent devices upon the movable frame 8 as 65 well as the driving elements and other parts, said rams or devices may, by the adjustment of the frame 8, be maintained in or moved to that position where they will be most effective in operation.

I claim:

1. A shield tunneling machine of the self-contained type, comprising an outer casing, internal tunneling mechanism, capable of rotation relatively to the outer casing and 75 means for effecting such rotation and for securing the casing and internal mechanism in their relatively adjusted positions.

2. A shield tunneling machine comprising an outer casing with internal circumferential rails, an internal tunneling structure having rollers mounted upon said circumferential rails and means for axially turning said structure within said casing and 80 securing the structure and casing in relatively adjusted position.

3. In a tunneling machine comprising an outer casing and an internal tunneling structure, means for circumferentially moving and fastening in position said structure comprising screw jacks connected to said structure and to said outer casing, the point of connection of said jacks to the said casing being variable circumferentially, substantially as and for the purpose described. 90

In testimony whereof I affix my signature in presence of two witnesses.

DOUGLAS WHITAKER.
